SEWING MACHINE

Harry E. Clayton, Holland, N. Y., assignor, by
mesne assignments, to Bagpak, Inc., a corpora-
tion of Delaware

Application April 16, 1941, Serial No. 388,723

11 Claims. (Cl. 112—197)

This invention relates to new and useful improvements in sewing machines and particularly seeks to provide novel stitch forming mechanisms adapted to form a double thread chain stitch employing an auxiliary binder thread of the type disclosed in my copending application, Serial No. 383,483, filed March 15, 1941.

The stitch forming mechanisms which comprise this invention are particularly adapted to be employed in connection with sewing machines of the general type disclosed in U. S. Letters Patent 2,043,149, granted to Howland F. Briggs on June 2, 1936 but obviously may be employed in connection with other suitable forms of sewing machines.

Heretofore, when filled paper bags or the like have been closed and sealed by the formation of a line of stitches across the formed closure, various forms of seams have been employed as well as various types of stitch formations. It has been known to employ a single thread chain stitch to secure the bag closure in its completely folded position wherein the collapsed bag mouth is folded back upon itself or to employ a double thread chain stitch for the same purpose. In the instances where the single thread chain stitch was employed, it has been observed that neither the thread entering the work on the needle side nor the interconnected loops on the work support side were so disposed or so proportioned that the apertures formed by the passage of the needle through the work were substantially sealed. Thus, a stitch closing of these forms of bag closures present difficulties in maintaining the bags in a sift-proof condition. In those types of stitched bag closures which employed the double thread chain stitch, it has been observed that substantially the same condition held true but to a somewhat less degree since the second series of interconnected loops formed by the looper thread of the double thread chain stitch provided a reasonably effective means for sealing those sides of the needle apertures which were presented towards the work support.

The above mentioned difficulties in connection with the formation of stitched bag closures through the employment of either single thread or double thread chain stitches have been overcome through the use of a modified double thread chain stitch formed through the use of mechanisms constructed in accordance with this invention and by which both ends of each individual needle aperture formed in the work are substantially sealed by certain portions of the loops comprising the stitches.

It is therefore an object of this invention to provide in a sewing machine novel mechanisms effective to form a stitch of the double thread chain stitch type which employs an auxiliary or binding thread serially formed into a plurality of spaced loops located upon the needle side of the work and encompassing the base portion of each needle thread loop.

Another object of this invention is to provide 10 a sewing machine of the character stated which includes a pair of cooperatively disposed loop forming elements located on the needle side of the machine and effective to form spaced loops in the auxiliary or binding thread.

Another object of this invention is to provide 15 a machine of the character stated in which the cooperatively disposed loop forming elements are operatively connected with the main drive shaft of the sewing machine with which they are associated.

Another object of this invention is to provide 20 a machine of the character stated which is effective to form a line of stitches of the double thread chain stitch type employing an auxiliary or binding thread on the needle side of the work and in which the loops of the auxiliary thread will substantially plug the needle apertures on the needle side of the work and the concatenated loops of the needle and looper threads will substantially plug the apertures of the work on the work support side.

Another object of this invention is to provide 25 a machine of the character stated which is simple in design, rugged in construction and economical to manufacture.

With these and other objects in view, the nature of which will become more apparent, the invention will be more fully understood by reference to the drawings, the accompanying detailed 30 description, and the appended claims.

In the drawings:

Fig. 1 is a fragmentary elevation of the closure portion of a bag including a line of stitches formed by mechanisms constructed in accordance 35 with this invention and taken from the needle side of the work;

Fig. 2 is a horizontal section taken along line 2—2 of Fig. 1;

Fig. 3 is a horizontal section taken along line 40 3—3 of Fig. 1;

Fig. 4 is a vertical transverse section taken along line 4—4 of Fig. 2;

Figs. 5 to 8 inclusive are somewhat conventionalized figures illustrating a complete cycle in 45 the formation of a stitch formed from mecha-

nisms constructed in accordance with this invention;

Fig. 9 is a fragmentary detailed elevation with parts in section taken along line 9—9 of Fig. 5;

Fig. 10 is a fragmentary detailed elevation with parts in section taken along line 10—10 of Fig. 6;

Fig. 11 is a fragmentary detailed elevation with parts in section taken along line 11—11 of Fig. 7;

Fig. 12 is a fragmentary detailed elevation with parts in section taken along line 12—12 of Fig. 8;

Fig. 13 is a motion diagram showing the movement of the auxiliary looper and indicating the paths of travel of the needle and the binder thread loop receiving fork;

Fig. 14 is an elevational view of a sewing machine including mechanisms constructed in accordance with this invention, the view being partially in section since portions of the mechanism shown in Fig. 16 have been broken away;

Fig. 15 is a transverse vertical section taken along line 15—15 of Fig. 14;

Fig. 16 is a horizontal section taken along line 16—16 of Fig. 14 and showing certain mechanism which has been broken away from Fig. 14.

Fig. 17 is an elevational view of the mechanism shown in Fig. 16 taken in a direction normal to the axis of the auxiliary looper elements; and

Fig. 18 is a fragmentary vertical section taken along line 18—18 of Fig. 16.

Referring to the drawings in detail, the invention, as illustrated, is embodied in a sewing machine of the type disclosed in the above-mentioned United States Letters Patent 2,043,149 and includes a main frame comprising a standard 5, an upper horizontal portion 6 and a depending post portion 7 spaced from the standard 5 to thereby completely define an inverted generally U-shaped frame. The horizontal portion 6 of the frame operatively houses the usual drive shaft 7a and associated driving pulleys generally indicated at 8. The drive shaft is operatively connected with the various elements which are normally effective to form a simple two-thread chain stitch in the manner clearly disclosed in the aforementioned United States Letters Patent 2,043,149 and which include a work support 9 secured on the inner face of the standard 5 adjacent the lower end thereof and feed dogs 10 associated therewith. A presser foot 11 is disposed in opposed relation to the work support 9 and is adapted to cooperate with the feed dogs in feeding of the work between the presser foot and the work support. The usual needle 12 is slidably mounted for lateral reciprocation on the lower end of the post 7 and has its axis aligned substantially normal to the general plane defining the work support. The main looper element 13 is oscillatably mounted in the lower end of the standard 5 in the usual manner and is adapted to cooperate with the needle 12 in forming a two-thread chain stitch. A needle thread 14 is threadably engaged in the needle 12 and a looper thread 15 is threadably engaged with the main looper 13 in the well known manner.

The lower end of the post 7 is provided with an offset bracket 16 including a bar portion 17 inclined relative to the axis of the needle 12. The forward end of the inclined bar 17 of the bracket is provided with a sleeve 18 pivotally secured thereto and adapted to support, for reciprocatory movement, one end of a mounting element 19 adapted to carry an auxiliary looper. The other end of the element 19 is provided with an eccentric strap 20 adapted to be operatively connected

with an eccentric 21 which serves to impart a combined oscillatory and reciprocatory movement to the element 19. The eccentric 21 is mounted on one end of a shaft 22 journalled on the bracket 16 and is adapted to be driven through connections which include a lower set of bevelled gears generally indicated at 23, a vertical shaft 24 and an upper set of bevelled gears generally indicated at 25. The upper bevelled gears 25 are adapted to be driven from the main drive shaft 7a through the medium of an auxiliary drive shaft 26 disposed in substantial parallelism therewith and operatively connected thereto through the medium of spur gears generally indicated at 27. The free end of the looper carrying element 19 is provided with an auxiliary looper element 28.

The forward end of the bar 17 is provided with an upstanding stud 29 which carries a sleeve 30 thereon. The upper end of the sleeve 30 is provided with a rearwardly projecting arm 31, the free end of which is provided with a roller cam follower 32. The lower end of the sleeve 30 is provided with a forwardly projecting arm 33 adapted to carry an auxiliary loop forming fork 34 having a bifurcated arm 35 and adapted to cooperate with the auxiliary looper element 28 in forming the loops of an auxiliary binder thread 36 threadably engaged with the auxiliary looper 28.

The roller cam follower 32 is operatively engaged with a cam 37 rigidly secured to the shaft 24 and effective to impart an oscillatory movement to the arm 31 and consequently to the loop forming fork element 34. Preferably, the arm 31 is spring biased against the cam 37 in order that contact therewith may be satisfactorily maintained, and the desired motion may be imparted to the fork 34 in a uniform manner.

Thus, it will be readily apparent that rotation of the main drive shaft 7a and its associated driving connections will effect the combined oscillation and reciprocation of the looper mounting element 19 and consequently effect movement of the auxiliary looper 28 through a generally elliptical path, a portion of which overlies the axis along which the needle 12 travels. Simultaneously with the movement of the looper element 28 the loop forming fork 34 will be oscillated laterally as a result of the driving connections between the cam 37 and the cam follower 32 mounted on the rock arm 31. The combined motions of the fork 34 and the looper 28 serve to form the auxiliary binder thread 36 into successively formed loops, the centers of which are disposed in coaxial relationship with the needle 12 prior to the time at which the needle penetrates the work preparatory to the beginning of a stitch.

In Figs. 5 through 8 of the drawings, there is illustrated the manner in which the various structural elements above described function to form a line of stitches. In Fig. 5 the needle 12 together with the auxiliary loop forming fork 34 and the auxiliary looper 28 are shown in their proper relative positions during the first stage of a stitch formation, the needle being at the beginning of its retractive stroke. In Fig. 6 the needle 12 has been retracted from engagement with the work W and the main looper 13 has been projected through the loop of the needle thread 14. At this stage of the cycle of stitch formation the auxiliary looper element 28 has moved upwardly and forwardly to the left to engage the binder thread 36 around the bifur-

cated end 35 of the loop forming fork 34. As shown in Fig. 7, the previously formed stitch has been partly tightened by feed of the work through the machine and the auxiliary looper 28 has moved over the fork 34 and has started to move downwardly between the fork 34 and the work W. The needle 12 at this stage of the cycle of stitch formation is approaching the work preparatory to the formation of another stitch. As the parts move from the position shown in Fig. 7 toward that shown in Fig. 8 the auxiliary looper 28 moves downwardly between the work W and that portion of the binder thread 36 which extends from the previously formed stitch to the end 35 of the fork 34. There is thus formed around the fork 34 a closed loop of binder thread 36. The auxiliary looper 28 moves out of the path of the needle 12 in time for the needle to pass through the loop while it is held by the fork 34 and thereafter the fork 34 moves out of the path of the needle 12 towards the position illustrated in Fig. 8. In Fig. 8 the feed step of the work through the machine has been completed and the needle 12 has been propelled through the loop formed in the binder thread 36 and is ready to pierce the work for the formation of another stitch. Figs. 9, 10, 11 and 12 of the drawings are elevational views which respectively correspond to Figs. 5, 6, 7 and 8 and more clearly show the exact manner by which a loop is formed in the binder thread 36. It should be noted that the lateral oscillation of the loop forming fork 34 is so timed that it effects the disengagement thereof from the binder thread 36 subsequent to the engagement of the needle 12 within the loop formed in the thread 36 and to position the loop forming fork in its proper location to be again engaged by the binder thread 36 preparatory to the formation of the next succeeding stitch. It should be further noted that by disposing the elliptical path of travel of the auxiliary looper 28 in a plane inclined to the path of travel of the needle 12 there is no necessity for providing more than just a two-motion movement to the auxiliary looper 28 as effected through the medium of the eccentric and strap connections.

Fig. 13 is a motion diagram corresponding generally to Figs. 5, 6, 7 and 8, showing the path of travel 28A of the auxiliary looper 28 and indicating at 34A and 12A, respectively, the paths of travel of the fork 34 and needle 12.

Figs. 1 to 4 of the drawings, inclusive, illustrate fragmentary portions of a complete line of the stitches, as applied to the closure seam of a filled paper bag or the like, and formed by the herein described mechanisms. It will be noted that the needle and looper threads together define a plurality of serially formed concatenated loops on the work support side of the seam. The needle side of the seam presents the normal appearance of a series of through and through stitches and, in addition, is provided with the auxiliary or binder thread 36 which is formed into a plurality of spaced connected loops which encompass the base portions of the respective needle thread loops on the needle side of the work. Thus, this modified two-thread chain stitch presents a stitch formation which is particularly adapted for use in conjunction with the closures of filled paper bags or the like, since the concatenated loops of the needle and looper threads on one side of the seam will effectively seal the needle apertures and the loops of the binder thread will effectively seal the needle aper-

tures on the other side of the seam to thereby provide a bag closure seam which is substantially siftproof in nature.

It is readily apparent that the novel, modified double thread chain stitch formed from mechanisms constructed in accordance with this invention provides several advantages particularly in connection with the closing of filled paper bags which have not heretofore been provided through the use of prior known stitch formations. It should be noted that the binder thread 36 rests flatly against the bag surface and therefore substantially and tightly encompasses the base portions of the needle thread loops, and thus substantially seals the needle apertures on the needle side of the work, and the concatenations of the needle and looper threads effectively seal the needle apertures on the work support side of the work and a substantially siftproof seam is thereby produced. Since the herein disclosed mechanism effects the formation of the binder thread 36 into a series of spaced loops joined by connecting thread portions, the whole of which lies flat against the adjacent surface of the work, any pull or strain tending to compact the needle thread and looper thread portions of the stitches together will be resisted by the tensile strength of the binder thread 36. Thus, the formed stitches cannot collapse or be drawn together without first breaking the binder thread. Furthermore, the provision of the binder thread in the manner illustrated tends to prevent rupturing of the stitch formation as a result of tearing of the bag material between adjacent needle holes under imposed strains. Preferably, the binder thread 36 during the stitch forming operations is drawn under the same degree of tension as the looper and needle threads in order that all slack may be fully taken up at the end of the formation of each stitch.

Thus, it will be seen that the herein disclosed invention provides novel improvements in a sewing machine which are effective to form a stitch of the double thread chain stitch type employing a binding thread serially formed into a plurality of spaced loops located upon the needle side of the work and encompassing the base portion of each needle thread loop, in which the binding thread loops are formed by a pair of cooperatively disposed loop forming elements located on the needle side of the machine, and which is simple in design, rugged in construction and economical to manufacture.

It is of course to be understood that certain details of arrangement and proportions of parts may be variously modified without exceeding the scope of the appended claims.

I claim:

1. In a sewing machine having a threaded needle, a threaded looper, and means for moving said needle and looper to form a series of concatenated needle thread and looper thread loops defining a line of two thread chain stitches; the combination of means associated with said needle for forming a binder thread into a plurality of spaced connected loops, each of said loops being formed at the beginning of a cycle of stitch formation whereby in the completed line of stitches said binder thread loops will be disposed on the needle side of the work, said last named means comprising an auxiliary looper, loop receiving means, and means to move said loop receiving means into and out of a position wherein it is adapted to receive a loop of binder thread formed by said auxiliary looper and to support said loop

in a position encompassing the path of travel of said needle until said needle has entered said binder thread loop, the movement of said loop receiving means away from said position releasing each successively formed binder thread loop for encompassing engagement with a needle thread loop.

2. In a sewing machine, a work support, a presser foot opposed to said work support, means to feed work between said work support and said presser foot, a reciprocatory threaded needle having its axis disposed substantially normal to the general plane of said work support, a threaded looper cooperatively disposed with respect to said needle, means for cyclicly moving said feed means, said needle and said looper for forming a line of stitches including concatenated needle thread and looper thread loops on the work support side, and means operatively connected with said moving means for serially forming a binder thread into a plurality of spaced connected loops located on the needle side of the work, said means for forming said binder thread into a plurality of spaced connected loops comprising an auxiliary looper, loop receiving means, and means to move said loop receiving means into and out of a position wherein it is adapted to receive a loop of binder thread formed by said auxiliary looper and to support said loop in a position encompassing the path of travel of said needle until said needle has entered said binder thread loop, the movement of said loop receiving means away from said position releasing each successively formed binder thread loop for encompassing engagement with a needle thread loop.

3. In a sewing machine, a work support, a presser foot opposed to said work support, means to feed work between said work support and said presser foot, a reciprocatory threaded needle having its axis disposed substantially normal to the general plane of said work support, a threaded looper cooperatively disposed with respect to said needle, means for cyclicly moving said feed means, said needle and said looper for forming a line of stitches including concatenated needle thread and looper thread loops on the work support side, a fork movable into and out of the path of travel of said needle, an auxiliary looper cooperatively disposed with respect to said fork and adapted to form a loop of binder thread therearound while said fork is positioned in the path of travel of said needle to thereby define a binder thread loop adapted to receive each needle thread loop as it is formed and encompass the base portion thereof, and means to actuate said fork and said auxiliary looper in timed relation with respect to said needle.

4. In a sewing machine of the class described, a fork movable into and out of the path of a threaded reciprocable needle, a looper cooperatively disposed with respect to said fork and adapted to form a loop of binder thread therearound while said fork is positioned in the path of travel of said needle, said binder thread loop being adapted to receive a needle thread loop and encompass the base portions thereof, and means to impart loop forming movements to said fork and said looper in timed relation relative to the movement of said needle.

5. In a sewing machine of the class described, a fork movable into and out of the path of a threaded reciprocable needle, means including a cam actuated rock arm for moving said fork, a looper cooperatively disposed with respect to said fork and adapted to form a loop of binder thread

therearound while said fork is positioned in the path of travel of said needle, said binder thread loop being adapted to receive a needle thread loop and encompass the base portions thereof, and means for moving said looper through a generally elliptical path enclosing said fork while said fork is positioned in the path of travel of said needle to thereby form said binder thread loop.

10 6. In a sewing machine of the class described, a movable fork disposed to one side of a reciprocatory needle, means for moving said fork into and out of the path of said needle, a looper disposed on the other side of said needle, said looper being adapted to form a loop of binder thread around said fork while said fork is positioned in the path of travel of said needle, and means for moving said looper through a generally elliptical path enclosing said fork while said fork is positioned in the path of travel of said needle to thereby form said binder thread loop in position to receive a needle thread loop and encompass the base portion thereof.

25 7. In a sewing machine of the class described, a movable fork disposed to one side of a reciprocatory needle, means including a cam actuated rock arm for moving said fork into and out of the path of said needle, a looper disposed to the other side of said needle, said looper being adapted to form a loop of binder thread around said fork while said fork is positioned in the path of travel of said needle, and means for moving said looper through a generally elliptical path enclosing said fork while said fork is positioned in the path of travel of said needle to thereby form said binder thread loop in position to receive a needle thread loop and encompass the base portion thereof.

30 8. In a sewing machine of the class described, a movable fork disposed to one side of a reciprocatory needle, means including a cam actuated rock arm for moving said fork into and out of the path of said needle, a looper disposed to the other side of said needle, said looper being adapted to form a loop of binder thread around said fork while said fork is positioned in the path of travel of said needle, and means including eccentric and strap connections for moving said looper through a generally elliptical path enclosing said fork while said fork is positioned in the path of travel of said needle to thereby form said binder thread loop in position to receive a needle thread loop and encompass the base portion thereof.

35 9. In a sewing machine of the class described, a fork movable into and out of a position in which a loop formed upon the prongs thereof encompasses the path of travel of a threaded reciprocable needle, a looper cooperatively disposed with respect to said fork and adapted to form a loop of binder thread around the prongs thereof while said fork is in said position, said binder thread loop being adapted to receive a needle thread loop and encompass the base portions thereof, and means to impart movement to said fork and loop forming movements to said looper in timed relation with the movement of said needle whereby to form and support said binder thread loop in position to receive said needle thread loop and to release said binder thread loop for encompassing engagement with the base portions of said needle thread loop when it is formed in the work.

40 10. In a sewing machine of the class described having a threaded reciprocable needle and means for reciprocating said needle to form needle

thread loops, the combination of loop receiving means movable into and out of a position in which a loop received thereby encompasses the path of travel of said needle on the needle side of the work, a looper cooperatively disposed with respect to said loop receiving means and adapted to form a loop of binder thread thereupon while said loop receiving means is in said position, said binder thread loop being adapted to receive a needle thread loop and encompass the base portions thereof, and means to impart movement to said loop receiving means and loop-forming movement to said looper in timed relation with the movement of said needle whereby to form a binder thread loop upon said loop receiving means when said loop receiving means is in said position and to move said loop receiving means from said position to release said binder thread loop for encompassing engagement with the base portion of said needle thread loop when it is formed in said work.

11. In a sewing machine of the class described having a threaded reciprocable needle and means

5 for reciprocating said needle to form needle thread loops, the combination of loop receiving means, means for moving said loop receiving means into and out of the path of said needle, a looper adapted to form a loop of binder thread around said loop receiving means when the same is positioned in the path of travel of said needle, means for moving said looper in a path encompassing said loop receiving means when the same is in the path of travel of the needle and encompassing the path of travel of said needle, and means for operating the needle reciprocating means, the moving means for said loop receiving means and the looper moving means in such timed relation as to form a loop of said binder thread in position to receive said needle as the same moves toward the work and to remove said loop receiving means from the path of said needle whereby to release said binder thread loop for encompassing engagement with the needle thread loop formed by said needle.

HARRY E. CLAYTON.
